UNITED STATES PATENT OFFICE.

CHARLES A. JOY, OF BORDEAUX, WASHINGTON.

OVERHEAD LOGGING SYSTEM.

1,170,645.

Specification of Letters Patent.

Patented Feb. 8, 1916.

Application filed May 21, 1915. Serial No. 29,614.

To all whom it may concern:

Be it known that I, CHARLES A. JOY, a citizen of the United States, residing at Bordeaux, in the county of Thurston and 5 State of Washington, have invented new and useful Improvements in Overhead Logging Systems, of which the following is a specification.

This invention relates to logging systems, 10 the object of the invention being to provide apparatus by means of which logs may be carried from various points to a common collecting point, the same means embodying in combination with an elevated sky line, a 15 carriage movable lengthwise thereof together with means for moving said carriage along the sky line, and brake mechanism by which the movement of the carriage and the log supported thereon may be arrested 20 at any moment, the entire mechanism being under the control of an engine stationed at a suitable point.

With the above and other objects in view, 25 the invention consists in the novel construction, combination and arrangement of parts, as herein described, illustrated and claimed.

In the accompanying drawings;—Figure 1 is a perspective view illustrating the entire logging system. Fig. 2 is an enlarged 30 side elevation of the carriage. Fig. 3 is a vertical longitudinal section through the carriage. Fig. 4 is a plan view thereof. Fig. 5 is an edge view of the carriage. Fig. 6 is a side elevation of one of the frame 35 plates of the carriage.

The carriage which will first be described comprises in the preferred embodiment thereof a pair of side plates 1 and 2 fastened together in spaced relation to each other by 40 suitable means. The carriage is adapted to be supported upon and to travel lengthwise of an elevated sky line 6 usually of wire, the carriage being provided with supporting wheels 7 and 8 the shafts or axles 9 and 10 45 of which are carried by the frame plates 1 and 2. In addition to the wheels 7 and 8 I provide a guard wheel 11 which is located under the sky line 6 and serves to prevent derailment of the carriage, all of the 50 wheels being peripherally grooved as shown to engage the line 6. The shaft 12 of the guard wheel is carried by one arm of a compensating lever 13 as shown in Fig. 2, said lever being pivotally mounted at 14 55 on the carriage and carrying at the extrem-

ity of its other arm a clevis 15 pivotally connected at 16 to the lever 13. The clevis 15 carries a pulley block 17 through which the main or haul in line hereinafter referred to passes. Adjacent to the clevis 15 60 the carriage is provided with a hole 18 to which the haul in or main line may be connected under certain conditions as in hauling on level ground.

19 designates a brake lever fulcrumed at 65 20 on the frame of the carriage, said lever having attached thereto a brake shoe 21 which bears against the guard wheel 11. Connected pivotally to the lever 19 at 22 is a rod 23 the opposite or upper extremity of 70 which is attached to a pin or pivot 24 connecting the inner and overlapping extremities of a pair of brake links 25 carrying at their outer opposite ends brake shoes 26 which bear against the supporting wheels 75 7 and 8 above referred to. Therefore, when the brake lever 19 is operated, all of the shoes 21 and 26 are pressed against their respective wheels to retard or stop the carriage beneath which the log is supported 80 and from which it is suspended as will hereinafter appear. Another clevis 27 is carried between the frame plates 1 and 2 and suspended by a pin or bolt 28 which is movable up and down in slots 29 in the carriage, the pin or bolt 28 being supported by a stem 30 the lower end of which is attached to said pin or rod and the upper end of which is supported by a coiled expansion spring 31 the lower end of which bears 90 against a plate 32 at the bottom of vertically extending slots 33 in the frame plates and the upper end of which bears against a plate or collar 34 above which the stem 30 is provided with a nut 35. 95

Referring now to Fig. 1 it will be seen that the carriage hereinabove described and which is now designated generally at A is supported by and movable along the sky line 6 also referred to above, said line being supported adjacent to its opposite ends by a head tree or support 36 and the tail tree or support 37. Beyond the tail support 37, after wrapping the sky line 6 one or more times around said tail tree, the end thereof 100 is carried to a stump or its equivalent indicated at 38 to form a guy line for said sky line. The other end portion of the sky line 6 passes through a head pulley block 39 and is then connected by block and tackle indi- 105 110

cated at 40 and connected to a stump 41 or its equivalent, to the drum 42 of a donkey engine designated generally at B. In this manner, the sky line 6 may be stretched 5 tightly between the head and tail trees so as to properly support the carriage and its load. Guy lines 43, 44 and 45 are extended from the head tree 38 to conveniently located stumps 46, 47 and 48 and other guy 10 lines 49 and 50 are extended from the tail tree 37 to conveniently located stumps 51 and 52.

53 designates the main or haul in line which passes through the pulley block 17 15 hereinabove described and thence through another pulley block 54 on a tag line 55 to the clevis 27 hereinabove described and as shown in Fig. 1. The tag line 55 is provided with a bull hook 56 by means of which 20 a log indicated at 57 is engaged and elevated preparatory to hauling the same toward the head tree 36. After leaving the block 17 the main or haul in line 53 passes over a head block 58 and thence downwardly to 25 another drum 59 of the engine B.

A haul back line 60 extends from a third drum 61 on the engine B upwardly through a head block 62 on the head tree and thence downwardly and through a series of yard- 30 ing blocks 63, 64 and 65 and then through a tail block 66 toward the carriage which has attached thereto another pulley block 67 through which passes a slack line 68 one 35 end of which has a swiveled connection with the pulley block 54 and the other end of which is attached to the brake lever 19 at 69. The length of the slack line 68 governs the width of the strip of the ground to be covered in the hauling in operation. Where 40 logs are to be hauled from beyond or behind the tail tree 37, the tail block 66 may be shifted to the position indicated at 66' in Fig. 1, the slack line 68 permitting a log to be engaged and lifted at such point.

45 From the foregoing description, taken in connection with the accompanying drawings, the operation of the logging system will now be understood.

The haul back line hauls the carriage out 50 along the sky line to the point where the log is to be hooked on. The carriage is then stopped and the bull hook on the end of the tag line is engaged with the log. The main or haul in line is then operated so as to raise 55 one end of the log clear of the ground as indicated in Fig. 1 and the log carriage then starts along the sky line in the direction of the head tree. When working on a steep grade or hill side, the log may start 60 to run but in such event it may easily be checked by holding back on the haul back line and applying the brake shoes to the wheels of the carriage. If desired, the log may be lifted clear of the ground by holding 65 back on the haul back line and winding

on the haul in or main line. One head tree is all that is required at one setting of the engine. The tail tree is changed each time a strip is logged or, in other words, cleared of logs. These strips may be just as wide 70 as desired, a new tail tree being selected and guyed before the old one is deserted and for this purpose a light line or what is termed a straw line is run out from the drum of the engine and fastened to the selected tail tree. 75 The lines hereinabove described are then drawn toward the head tree from the old tail tree and are propelled outwardly toward the new tail tree along the straw line, the haul back line being used for the purpose. 80 The sky line is then made fast and the logging operation resumed.

What I claim is:-

1. In a logging system, the combination 85 of supporting uprights located at a distance from each other, an elevated sky line extending from one upright to the other, a wheeled carriage supported by and movable along said sky line, a main draft line connected at two points with said carriage, a tag line having a pulley block through which said main draft line passes between said two points, a slack line connecting said pulley block with the carriage, and a haul back line having a pulley block 95 through which said slack line passes.

2. In a logging system, the combination 100 of supporting uprights located at a distance from each other, an elevated sky line extending from one upright to the other, a wheeled carriage supported by and movable along said sky line, a main draft line connected at two points with said carriage, a tag line having a pulley block through which said main draft line passes between 105 said two points, a slack line extending from said pulley block to the wheeled carriage, an engine having a winding drum for the sky line, a haul back line having a pulley through which said slack line passes, a 110 drum for the main draft line, and a drum for the haul back line.

3. In a logging system, the combination 115 of supporting uprights located at a distance from each other, an elevated sky line extending from one upright to the other, a wheeled carriage supported by and movable along said sky line, a main draft line connected at two points with said carriage, a tag line having a pulley block through 120 which said main draft line passes between said two points, a slack line, a haul back line and a wheel brake mechanism on said carriage controlled by the haul back and slack lines.

4. In a logging system, the combination of 125 supporting uprights located at a distance from each other, an elevated sky line extending from one upright to the other, a wheeled carriage supported by and movable 130

along said sky line, a guard wheel on the carriage engaging the bottom of the sky line, a main draft line connected at two points with said carriage, and a tag line having a pulley block through which said main draft line passes between said two points.

In testimony whereof I affix my signature in presence of two witnesses.

CHARLES A. JOY.
